UNITED STATES PATENT OFFICE.

FRANK L. CRINELLA, OF VIRGINIA, MINNESOTA.

POSTHOLE-DIGGING OUTFIT.

Application filed November 30, 1920. Serial No. 427,421.

To all whom it may concern:

Be it known that I, FRANK L. CRINELLA, a citizen of the United States, residing at Virginia, in the county of St. Louis and 5 State of Minnesota, have invented a new and useful Posthole-Digging Outfit, of which the following is a specification.

This invention relates to post hole diggers, the object being to provide an implement consisting of a combination of tools, each of which is adapted to perform a 10 different function in the act of digging a hole, the several parts so constructed as to be interchangeable with the handle, the latter preferably being built up in sections, whereby it may be lengthened according to 15 the depth of the hole, the several sections being interchangeable.

In the accompanying drawings:

- 20 Fig. 1 is an end view of the digger;
- Fig. 2 is a side view of the digger;
- Fig. 3 is an end view of one of the handle sections;
- Fig. 4 is a side view of one of the sections;
- 25 Fig. 5 is an end plan view thereof;
- Fig. 6 is an end view of one of the sections;
- Fig. 7 is a side view of one of the short sections of the handle;
- 30 Fig. 8 is an end view thereof;
- Fig. 9 is a front view of the chopping-bit;

- Fig. 10 is an end view of the interchangeable top of the handle;
- 35 Fig. 11 is a side view of the interchangeable handle;
- Fig. 12 is an end view thereof;
- Fig. 13 is an end view of the chopping-bit;
- 40 Fig. 14 is a side view of the chopping-bit;

- Fig. 15 is a side view of the moil;
  - Fig. 16 is a front view of the moil.
- As disclosed in Figs. 1 and 2, the cutting blade preferably consists of a substantially U-shaped member *a*, the parallel edges of which are adapted to taper slightly toward the bottom, and serve to retain the ground while the digger is being lifted out of the 50 hole, the inner end of this member *a* preferably provided with a screw-threaded member *b*, and a shoulder *c* being provided at the bottom of the screw-thread to take up the charge when in use.

- 55 The letter *d* indicates the first section of

the handle, which is of sufficient length for ordinary purposes, the ends of this member *d* preferably being screw-threaded as at *e*, *e*, whereby the section is secured to the cutting-blade. Received upon the end of this member *d* is a member *f* as shown in Fig. 11, 60 acting as the top of the handle when one section only is being used. If it be desirable to lengthen this handle, according to the depth of the hole, an intermediate section *g* 65 may be first attached to the section *d*. This section *g* preferably is provided at one end with the external screw-threads *h*, and at the opposite end with internal screw-threads *i*, whereby said section *g* may be attached to the member *d* and the member *f* may be attached to the member *g*. The members *f* and *g* serve to lengthen the handle according to 70 the depth of the hole being dug.

Disclosed in Figs. 15 and 16 is a moil *j* 75 which may be attached to the handle, when it is desirable to pick loose lumps of hard ground or rocks, which may be encountered in digging the hole.

Disclosed in Figs. 9 and 14 is a chopping-bit *k* which likewise is adapted to be attached to the sectional handles, this tool serving as a chisel which is used for cutting off roots, trees, or breaking any rocks which may be encountered in the process of digging. 80

I claim:

1. A post hole digger comprising a digger-blade of substantially U-shaped cross section, the outer parallel edges thereof tapering from top to bottom, and provided at its inner end with a screw-threaded portion, a handle adapted to be detachably secured to said screw-threaded portion, said handle consisting of one or more sections. 90

2. A post hole digger comprising a digger-blade substantially U-shaped in cross-section, the outer parallel edges thereof tapering from top to bottom, and provided at its inner end with a screw-threaded portion, a 100 handle adapted to be detachably secured to said digger, said handle consisting of a plurality of detachable sections comprising a main section, an intermediate section, and a top portion.

FRANK L. CRINELLA.
